PULVERIZER

Ervin G. Bailey, Easton, Pa., Perry R. Cassidy,
Short Hills, N. J., and Ralph M. Hardgrove,
Westfield, N. J., assignors, by mesne assign-
ments, to The Babcock & Wilcox Company,
Newark, N. J., a corporation of New Jersey

Application September 6, 1929, Serial No. 390,698
Renewed July 26, 1934

15 Claims. (Cl. 83—45)

The present invention relates to an improved construction of a pulverizer or grinding mill of the type in which the grinding parts form a plurality of grinding stages successively acting upon the material undergoing pulverization, and more particularly to a multi-stage pulverizer in which upper and lower rows of rolling grinding elements are positioned between corresponding pairs of superposed grinding rings and driven by a common rotary grinding ring to form upper and lower grinding stages. The improved pulverizer is especially adapted for grinding coal, but is also adapted for grinding other materials.

The general object of our invention is the provision of a pulverizer or grinding mill of the general type described which is especially characterized by its high capacity, high degree of fineness of output, substantially uniform wear of the grinding parts of the several stages, and relatively low power consumption. A further and more specific object is the provision of simple and effective means for normally maintaining a desirable level of material in one grinding stage and reducing the rate of flow of material while therein, to thereby increase the fineness of the material delivered to a successive grinding stage.

The invention will be understood from the description in connection with the accompanying drawings in which Fig. 1 is a vertical section through an illustrative embodiment of the invention; Fig. 2 is a section along the line 2—2 of Fig. 1; Fig. 3 is a section along the line 3—3 of Fig. 1; Fig. 4 is a plan view taken along the line 4—4 of Fig. 1; and Fig. 5 is an enlarged view of the flow restricting provisions shown in Fig. 1.

In the drawings reference character 1 indicates a base or support to which the bottom 2 of the grinding mill is attached by means of bolts 3. The wall 4 of the mill extends upwardly from the base 2 and is supported thereon. The wall 4 constitutes a casing which surrounds the grinding elements and other parts of the machine. A cylindrical outlet 5 for the fine particles of ground material is provided at the top of the casing 4.

A wind box 6 is provided around the lower portion of the wall 4 and an inlet 7 for air under pressure from any convenient source leads to the wind box 6.

A lower stationary grinding ring 8 rests upon supporting posts 9 on the bottom 2 and is provided with a ball race 10 for a circular row of grinding balls 11.

A rotatable driving ring 12 is located above the row of balls 11 and is provided with ball races 13

along its upper and lower edges. A circular row of grinding balls 14 is located above the ring 12 and contacts therewith.

A yoke 15, having arms that extend between pairs of lugs 16 on the inner surface of the rotatable ring 12, is driven by the vertical shaft 17, which is in turn driven through reduction gearing by the motor 18. The described arrangement of the yoke arms and lugs 16 provides a floating drive connection for the grinding ring 12.

A non-revolvble ring 19 with a ball race 20 along its lower edge is located above the row of balls 14. A pressure ring 21 contacts with the upper edge of the ring 19 and is provided with an upwardly extending flange 22 along its inner edge. Lugs 21' (Fig. 3) are attached to the casing 4. These lugs project into vertical slots between lugs 21" that are attached to the ring 21 so that the ring 21 is prevented from rotating, but is permitted to move up and down.

A ring 23, similar to the ring 21, but having a depending flange 24 near its inner edge, is located above the ring 21. Lugs 25 on the inside of the flange 22 and lugs 26 on the inside of the flange 24 are connected by bolts 27 so that the rings 21 and 23 may move toward and away from each other and are limited in the distance they can move apart by the bolts 27. A series of compression springs 28 are interposed between the rings 21 and 23.

Spherically shaped sockets 29 are attached to the upper edge of the ring 23. Rods 30 with ball shaped lower ends are connected to the sockets 29. The upper ends of the rods 30 are threaded and threaded sleeves 31 are screwed on them. The sleeves 31 are revolvably supported in bearings 32 on the outside of the casing 4. The sleeves 31 are provided with external gears 34 that are driven by worm gears on the shafts 35 of the hand wheels 36. The rods 30 pass through stuffing boxes 37 in the wall 4 to prevent escape of dust.

A conically shaped classifier or separator 40 is located below the outlet 5 with its upper edge extending above the lower edge of the outlet 5.

A conically shaped deflector 41 extends from the upper edge of the inside of the ring 12 and has a cylindrical upper edge extending into the hollow portion of the ring 19. An outlet 42 extends from the lower portion of the classifier 40 into the space between the deflector 41 and the balls 14.

A feed spout 43 also extends through the upper portion of the wall 4 into the space between the deflector 41 and the balls 14.

An annular outwardly flaring wall or baffle 44 is located around the outside of the row of balls 14 and is of somewhat larger diameter than the diameter of the row of balls. The lower edge of the 5 wall or baffle 44 rests upon an annular ring plate 45 that is L-shaped in cross section and is adjustable up and down by means of arms 46 attached thereto that are supported by rods 47 having adjusting nuts at the upper ends thereof 10 on opposite sides of brackets 48 which are attached to the wind box 6. A flat plate 49 is attached to the lower edge of the horizontal flange of the ring plate 45. The inside diameter of the flat ring 49 is approximately the same as the outside 15 diameter of the driving ring 12, so that the space for escape of material from the outside of the row of balls 14 downwardly can be adjusted to regulate the size of particles that pass therethrough by the position of the flat plate 49.

20 Openings 50 are provided through the wall 4 from the lower portion of the wind box 6. A wall of sheet metal 51 is provided from the grinding ring 8 to the wall 4 at a point above the upper ends of the openings 50. Ports 52 are provided 25 through the annular ring 9 from the space outside of the wall 51 to permit air to pass from the box 6 through the inside of the ring 8.

The operation is as follows:

The ring 12 is driven by the yoke 15, thus causing 30 the rows of balls 11 and 14 to turn against the grinding surfaces. Material to be ground is introduced through the feed pipe or conduit 43 into the space along the outside of the deflector 41 from which it passes through the row of balls 14 and receives preliminary grinding. The baffle 44 retains the material until it is sufficiently ground to pass through the space between the ring plate 49 and the ring 12. Partially ground material falls through this space and may fill the 35 space inside of the wall 51 from which it passes through the row of balls 11 which finish the grinding. The fine particles are picked up by air entering through the inlet 7 and passing from the box 6 through the ports 52 along the inside of the row of balls 11. The air carrying the ground 40 particles passes upwardly and around the upper edge of the separator 40 and under the lower edge of the outlet 5. The heavier particles are separated out and fall to the bottom of the separator 45 40 from which they pass through the outlet 42 into the space outside of the deflector 41 and thence again through the rows of balls to be further ground.

The pressure of the springs 28 can be regulated 50 by turning the hand wheels 36, thus varying the pressure between the grinding balls and the grinding rings. Also, the rate of grinding is automatically regulated by the rate of feed of material, since the layers of material that are being 55 ground cause the ring 21 to rise and compress the springs 28, thereby creating greater pressure upon the grinding balls. At very light loads the bolts 27 prevent the ring 21 from descending below a predetermined position thereby relieving the pressure 60 upon the balls when only thin layers of the material are present between the balls and the grinding surfaces.

The rods 30 can be drawn upwardly by means 65 of the hand wheels 36, thus carrying the rings 70 23, 24 and 19 upwardly so that the balls or other worn or injured parts can be reached for replacement or repair. The balls 14 of the upper row that produce the initial grinding may, if desired, be made larger than the balls in the row 11. The 75 size of the particles that pass from the upper

row of balls to the lower roll of balls is regulated by the position of the ring plate 49 relative to the upper edge of the grinding ring 12.

While in accordance with the provisions of the statutes we have illustrated and described herein 5 the best form of our invention known to us, those skilled in the art will understand that changes may be made in the form of the apparatus and character of the carrier medium disclosed without departing from the spirit of the invention 10 covered by our claims, and that certain features of our invention may sometimes be used without a corresponding use of other features. In our claims, the word "air" is used generically to cover any gaseous carrier medium suitable for removing 15 pulverized material in the manner described.

We claim:

1. In a grinding mill, a plurality of rows of 20 rotating grinding elements, means for feeding material to one row of said elements in one direction and to another row in the opposite direction, and means to limit the size of particles that pass from one row to the other.

2. In a grinding mill, a plurality of rows of 25 rotating grinding elements, means for feeding material to one row of said elements in one direction and to another row in the opposite direction, and means to limit the size of particles that pass from one row to the other, said last named means comprising an adjustable ring. 30

3. In a grinding mill, a plurality of rows of 35 rotating grinding elements, means for feeding material to one row of said elements in one direction and to another row in the opposite direction, a stationary baffle around the outside of one 40 row of said elements, and means to cause an air current to pass upwardly through the inside of said rows of elements.

4. In a grinding mill, two circular rows of 45 rotating grinding elements, a driving ring between said rows, a deflector inside of one of said rows, a baffle along the outside of said row of elements, means for adjusting said baffle vertically to vary the distance between it and said driving ring and a feed inlet extending into the space between said 50 row and said deflector.

5. In a grinding mill, two circular rows of 55 rotating grinding elements, a driving ring between said rows, a deflector inside of one of said rows, an adjustable plate along the outside of said row 60 of elements, means to adjust said plate to regulate the size of particles passing to the other row of elements, and a feed inlet extending into the space between said row and said deflector.

6. A grinding mill comprising a casing having 65 an inlet for material to be ground and an outlet for ground material, a plurality of vertically spaced grinding rings in said casing, upper and lower circular rows of rolling grinding elements positioned between corresponding pairs of grinding rings and cooperating therewith to form successive upper and lower grinding stages, each receiving material to be ground at one side of the corresponding row of elements and discharging ground material at the other side, and means 70 forming an adjustable gap at the discharge side of said upper row of elements for substantially restricting the flow of material while in said upper stage.

7. An air-swept grinding mill comprising a 75 casing having an inlet for material to be ground and an outlet for ground material in the upper part of said casing, a plurality of vertically spaced grinding rings in said casing, upper and lower circular rows of rolling grinding elements 80

- positioned between corresponding pairs of grinding rings and cooperating to form successive upper and lower grinding stages, each receiving material to be ground at one side of the corresponding row of elements and discharging ground material at the other side, baffle means for substantially restricting the flow of material while in said upper stage, and means for passing a stream of air upwardly through said casing to 5 said casing outlet past and receiving ground material from the discharge side of said lower row of elements.
8. An air-swept grinding mill comprising a casing having an inlet for material to be ground 10 and an outlet for ground material in the upper part of said casing, a plurality of vertically spaced grinding rings in said casing, upper and lower circular rows of rolling grinding elements positioned between corresponding pairs of grinding rings and cooperating therewith to form successive upper and lower grinding stages, each receiving material to be ground at one side of the corresponding row of elements and discharging ground material at the other side, baffle 15 means at the discharge side of said upper row of elements for substantially restricting the flow of material while in said upper stage, and means for passing an annular stream of air upwardly through said casing to said casing outlet and 20 mainly adjacent to and past the discharge side of one of said rows of elements.
9. An air-swept grinding mill comprising a substantially air-tight casing having an outlet for ground material in the upper part thereof 25 and enclosing parts forming successive vertically spaced upper and lower grinding stages, means for delivering material to be ground to said upper grinding stage, means at the discharge side of said upper stage arranged to substantially restrict the flow of material while in said upper stage, and means for directing a stream of air upwardly through said casing adjacent to and mainly past the discharge side of said lower grinding stage and conveying the material 30 discharged therefrom towards said casing outlet.
10. An air-swept grinding mill comprising a substantially air-tight casing having an outlet for ground material in the upper part thereof and enclosing vertically spaced upper, intermediate and lower grinding rings, circular rows 35 of rolling grinding elements positioned between said upper and intermediate and said intermediate and lower grinding rings and cooperating therewith to form an upper grinding stage having an outward flow of material therethrough and a lower grinding stage receiving material from said upper stage and having an inward flow of material therethrough, a drive shaft arranged axially of said grinding rings, means forming a 40 rotary drive connection between said shaft and intermediate grinding ring, means preventing rotation of said upper and lower grinding rings, means for delivering material to be ground to the inner side of said upper row of elements, and means at the outer side of said upper row of elements for substantially restricting the outward flow of material while in said upper stage, an air box surrounding said casing, and means for directing an annular stream of air from said 45 air box upwardly through said casing adjacent to and mainly past the inner side of said lower row of elements and conveying the material discharged therefrom towards said casing outlet.
11. A grinding mill comprising a casing having 50 an inlet for material to be ground and an outlet 55 for ground material, a plurality of vertically spaced grinding rings in said casing, upper and lower circular rows of rolling grinding elements positioned between corresponding pairs of grinding rings and cooperating therewith to form successive upper and lower grinding stages, each receiving material to be ground at one side of the corresponding row of elements and discharging ground material at the other side, and an upwardly flaring frusto-conical baffle arranged at the discharge side of and out of contact with said upper row of elements and extending above the center line thereof and positioned to cooperate with the lower grinding ring of said upper stage in substantially restricting the rate of flow of material while in said upper stage.
12. A grinding mill comprising a casing having an inlet for material to be ground and an outlet for ground material, a plurality of vertically spaced grinding rings in said casing, upper and lower circular rows of rolling grinding elements positioned between corresponding pairs of grinding rings and cooperating therewith to form successive upper and lower grinding stages, each receiving material to be ground at one side of the corresponding row of elements and discharging ground material at the other side, and an upwardly flaring frusto-conical baffle arranged at the discharge side of and out of contact with said upper row of elements and extending above the center line thereof and positioned to cooperate with the lower grinding ring of said upper stage in substantially restricting the rate of flow of material while in said upper stage.
13. A grinding mill comprising a casing having an inlet for material to be ground and an outlet for ground material, a plurality of vertically spaced grinding rings in said casing, upper and lower circular rows of rolling grinding elements positioned between corresponding pairs of grinding rings and cooperating therewith to form successive upper and lower grinding stages, each receiving material to be ground at one side of the corresponding row of elements and discharging ground material at the other side, and means at the discharge side of said upper row of elements for substantially restricting the rate of flow of material while in said upper stage comprising a normally stationary annular plate extending from the inner wall of said casing toward but slightly spaced from a relatively movable rotating grinding ring to provide an annular gap therebetween for the passage of material to said lower stage.
14. A grinding mill comprising a casing having an outlet for ground material and enclosing vertically spaced upper, intermediate and lower grinding rings, circular rows of rolling grinding elements positioned between said upper and intermediate and said intermediate and lower grinding rings and cooperating therewith to form upper and lower grinding stages, means for delivering material to be ground to the inner side of said upper row of elements, the parts forming said lower stage being constructed and arranged to receive material from the outer side of said upper stage and to cause an inward flow of material through said lower stage, and baffle means at the outer side of and out of contact with said upper row of elements and arranged to cooperate with the lower grinding ring of said upper stage to normally restrict substantially the rate of outward flow of material while in said upper stage.
15. A grinding mill comprising a casing having an outlet for ground material and enclosing ver-

tically spaced upper, intermediate and lower grinding rings, circular rows of rolling grinding elements positioned between said upper and intermediate and said intermediate and lower grinding rings and cooperating therewith to form upper and lower grinding stages, a drive shaft arranged axially of said grinding rings, means forming a rotary drive connection between said shaft and intermediate grinding ring, means preventing rotation of said upper and lower grinding rings, means for delivering material to be ground to the inner side of said upper row of elements, the parts forming said lower stage being

constructed and arranged to receive material from the outer side of said upper stage and to cause an inward flow of material through said lower stage, and baffle means at the outer side of and out of contact with said upper row of elements and arranged to cooperate with the lower grinding ring of said upper stage to normally restrict substantially the rate of outward flow of material while in said upper stage.
